UNITED STATES PATENT OFFICE.

FRIEDRICH BOLEG, OF ESSLINGEN, GERMANY, ASSIGNOR TO GESELLSCHAFT ZUR VERWERTUNG DER BOLEG'SCHEN WASSERLÖSLICHEN MINERALÖLE UND KOHLENWASSERSTOFFE, GESELLSCHAFT MIT BESCHRÄNKTER HAFTUNG OF BERLIN, A CORPORATION OF GERMANY.

PROCESS OF MAKING WATERY SOLUTIONS OF MINERAL AND ROSIN OILS.

SPECIFICATION forming part of Letters Patent No. 761,939, dated June 7, 1904.

Application filed September 18, 1900. Serial No. 30,432. (No specimens.)

To all whom it may concern:

Be it known that I, FRIEDRICH BOLEG, chemist, of Bahnhofstrasse 1, Esslingen-on-Neckar, Württemberg, Germany, have invented a new 5 Process of Manufacturing Clear and Permanent Watery Solutions of Mineral and Rosin Oils, of which the following is a full, clear, and exact description.

The object of my present invention is to produce clear and permanent watery solutions of mineral and rosin oils from the soluble or emulsifiable mixtures of mineral and rosin oils. In producing these oils a suitable mineral oil is put into a washing-trough with a certain percentage of crude anhydrous light colored rosin oil and is then treated with direct steam at about five atmospheres pressure. The mixture is boiled at not more than 100° to 105° Celsius. Then from five to seven percent of caustic-soda 15 lye of 40° Baumé is added, according to specific gravity. The mixture is maintained for twenty or thirty minutes in a boiling state and treated until the oil is seen to clearly separate from the soap-lye. After allowing 20 the whole to stand for three-fourths of an hour the clear oil is drawn off.

In order to produce the said watery solutions, I proceed as follows: The oils produced in the manner above referred to are intimately 25 mixed in an oxidizing apparatus or in a pressure-still by means of air under pressure at 50° to 60° Celsius with about fifty, sixty-six and two-thirds, seventy-five (or less or more) parts of distilled water. All mineral oils, the 30 light as well as the heavy, may be used.

According as oils of a more or less specific gravity are used and according to the quantity of water, I add to the said mixture at the same time a quantity of suitably-prepared 35 gelatin—that is to say, one-eighth to one-half per cent. dissolved in one hundred per cent. of water—which is dissolved therein. The addition of gelatin serves as a regulating agent of the desired viscosity and has the 40 object to produce permanent solutions. In-

stead of gelatin, if desired, caoutchouc may be used to increase the viscosity in quantity not exceeding one-half per cent.; but in this event the caoutchouc is dissolved directly in the hot oil. After having added the gelatin 50 the mixture is oxidized by means of compressed air at a slowly-rising temperature—that is to say, to 115° Celsius when the specific gravity of the oil is 0.885 to 0.900 and 125° Celsius in oils of a specific gravity 55 from 0.900 to 0.925—and by continually renewing the evaporating water. This process is continued until the mixture becomes quite clear or maintains itself clear in cooling it for trial on a glass plate, this operation enduring 60 about forty-five to sixty minutes.

If as an alternative process the oil mixture is effected in a pressure-still or distilling apparatus, it is subjected therein after having cut off the supply of the compressed air to a 65 pressure of one to one and one-half atmospheres, (one atmosphere in oils having a less specific gravity than 0.900 and one and one-fourth to one and one-half atmospheres in oils the specific gravity of which is greater 70 than 0.900.) This operation is continued about during half an hour by heating the mixture by means of indirect steam. The permanency of clearness of the solutions may be ascertained also in this case by cooling them 75 for trial on a glass plate before the apparatus is being put out of action.

The use of the second method is preferable, because the watery-oil solutions produced under pressure have a greater permanency 80 and resistance against heat as well as against cold. This is also the reason for which the described clear watery-oil solutions are to be preferred to the troubled solutions and mixtures or emulsions.

What I claim, and desire to secure by Letters Patent, is—

1. The herein-described process of manufacturing clear and permanent watery solutions of mineral and rosin oils consisting in 90

treating a mixture of a mineral oil and a crude anhydrous rosin-oil with steam, boiling the mixture and adding lye, separating the oil from the soap-lye, and then treating said oil with distilled water and compressed air substantially as described.

2. The herein-described process of manufacturing clear and permanent watery solutions of mineral and rosin oils consisting in treating a mixture of a mineral oil and a crude anhydrous rosin-oil with steam, boiling the

mixture and adding lye, separating the oil from the soap-lye, and then treating said oil with distilled water containing an agglutinant and compressed air substantially as described. 15

In witness whereof I have hereunto set my hand in presence of two witnesses.

FRIEDRICH BOLEG.

Witnesses:

KARL BORCH,

HERMANN WAGNER.
